5 Claims. (Cl. 337—187)

ABSTRACT OF THE DISCLOSURE

Tapered inserts hold the blade-type terminals of an electric component wedged into tapered rabbets in conductive adapters. A jacking feature associated with each insert facilitates its easy removal for replacement of the component.

This invention relates generally to the transmission of electric power and, more particularly, to the manner in which circuits are fused.

Current-limiting fuse holders with spring clips to hold the fuses in place and provide an electrical connection are known. However, available holders of this type are not satisfactory in industrial applications where high current in the range of 60 to 600 amps is required because dissipated heat tends to anneal the clips and cause a progressive failure of the connection. Consequently, current-limiting fuses are often bolted to terminal connectors, thus insuring a tight connection throughout the service life of the fuse. Replacement of bolted fuses is time-consuming and requires the use of wrenches to make the necessary connections.

Such difficulties have been avoided and the advantages disclosed herein have been achieved with a fuse holder which includes a channel-shaped support member and a conducting adapter at each end of the channel member, each adapter having a tapered rabbet. A tapered insert is carried in each rabbet and telescoped on a bolt threaded into the adapter. Means are provided to positively engage the inserts in the rabbets with a wedging action which insures a tight electrical connection between blade terminals on the fuse, the inserts and the adapters and to release the wedging action for removal of the terminals.

Structural details of a preferred embodiment will become apparent in the following specification wherein reference is made to the accompanying drawing. In the drawing, FIGURE 1 is a perspective view of the fuse holder and a blade-type current-limiting fuse; FIG. 2 is a fragmentary top view showing one end of the holder and a fuse; and FIG. 3 is a partially sectioned end view of the fuse and holder.

In the illustrated embodiment, a fuse 10 having blade-type terminals 12 is shown positioned in a fuse holder or circuit connection 14. Each blade 12 is fitted between a tapered insert 16 and an adapter 18. Each insert 16 has a bolt hole therethrough and is held in place by the head 19 on a bolt 20. Heads 19 are wing nuts threaded on the upper ends of bolts 20 and held against relative rotation by lock pins.

Circuit connection 14 also has a channel-shaped support member 22 made from an insulating material to allow mounting close to ground or other conductors. At each end of support 22, an adapter 18 is held by suitable fasteners. The adapter shown in FIGS. 2, 3 has a convergent longitudinal rabbet defined by surfaces 24, 26, 28,

2

with surface 26 tapered inwardly to the bottom surface 24 and with surface 28 perpendicular to surface 24. Bolt 20 is threaded into a tapped hole 30 in the bottom of adapter 18. Bolt 20 has an integral collar flange 32 between insert 16 and rabbet surface 24.

Adapters 18 and inserts 16 are made from electrically conductive material such as copper. Each adapter 18 has a binding post or screw 29 which is adapted to receive a terminal connector in the circuit to be fused.

Circuit connection 14 is assembled by placing fuse 10 in support 22 and fitting each blade terminal 12 between an insert 16 and the rabbet surface 28 of an adapter 18, with the blade resting on surface 24 of the adapter. As head 19 is rotated clockwise by hand, insert 16 is forced against surface 26 in a wedging action which insures a tight electrical connection. In removing the fuse 10, head 19 is turned counterclockwise, which results in bolt 20 backing out of threaded aperture 30 until collar 32 is forced against insert 16. The resultant jacking force loosens the tight connection between insert 16, blade 12 and adapter 18 to such an extent that the fuse may be lifted from connection 14.

Among the advantages of the illustrated connection is the manner in which fuse 10 is isolated from other electrical equipment by the insulating support 22 and thereby provides for more compact electrical installations. The support may also be part of a molded-case circuit breaker using current-limiting fuses. The tapered rabbet-insert-assemblies not only hold the blade terminals in a vise grip but also allow for insertion and removal of the fuse, using only the fingers, in a minimum of time and without the use of tools.

The connection is useful for any fuse or other type of electric component which has flat or leaf-like terminals. Instead of a head 19, a lever-operated camming action could be provided to position each insert 16. Alternatively, when the fuse holder is located in a closely confined, hard-to-reach space, a hex nut may be substituted for wing nut 19 so that a socket and extension may be used to reach and position the inserts. Other changes and modifications of a similar nature will occur to those skilled in the art without departing from the spirit of this invention which is accordingly intended to be limited only by the scope of the appended claims.

Having thus described the invention, what is claimed as new and desired to be secured by Letters Patent is:

1. A connection for blade terminals, said connection comprising: a channel-shaped support of insulating material; a conducting adapter mated with and mounted in the support and provided with a tapered rabbet; a tapered insert having a bolt hole therethrough, there being a threaded aperture in said adapter adapted to register with the bolt hole; and a bolt extending through said hole into the threaded aperture, said bolt being adapted to wedge the insert against a blade terminal located in the rabbet and having an integral flange between the adapter and insert for jacking the latter away from the adapter.

2. A circuit connection for an electric component having blade terminals, said connection comprising: a channel-shaped support of insulating material; a spaced pair of conducting adapters mated with and mounted in the support, each provided with a tapered rabbet; a pair of tapered inserts, each having a bolt hole therethrough, there being threaded apertures in said adapters adapted to register with the bolt holes; and a bolt extending through each hole into an aperture, said bolts being adapted to wedge the inserts against blade terminals located in the

respective rabbets, each bolt having an integral flange between its adapter and insert for jacking the latter away from the adapter.

3. The connection of claim 2 wherein the tapered rabbets are convergent.

4. The connection of claim 2 wherein the jacking flange on each bolt is a collar.

5. The connection of claim 2 wherein the bolt has a head in the shape of a wing nut.
